[57] CLAIM

The ornamental design for a pneumatic tire for vehicles, as shown and described.

DESCRIPTION

FIG. 1 is a front view of a pneumatic tire for vehicles showing my new design, it being understood that the tread pattern repeats uniformly throughout the circumference of the tire;

FIG. 2 is a rear view;

FIG. 3 is a left side view (the right side view being a mirror image);

FIG. 4 is a fragmentary view of the design shown in FIG. 1. FIG. 5 is a section view taken along line 5—5 in FIG. 4; and, FIG. 6 is a perspective view.
